WELL CASING CEMENTING PLUG AND
VALVE DEVICE

Reuben C. Baker, Coalinga, Calif., assignor to
Baker Oil Tools, Inc., Vernon, Calif., a corpora-
tion of California

Original application January 12, 1948, Serial No.
1,843. Divided and this application November
14, 1949, Serial No. 127,187

4 Claims. (Cl. 166—1)

1

The present invention relates to subsurface well devices, and more particularly to combination plug and valve devices adapted for downward movement through well conduits in the performance of certain desirable functions therein.

This application is a division of my application for "Ported Cementing Apparatus," Serial No. 1,843, filed January 12, 1948, now Patent No. 2,602,510.

An object of the present invention is to provide an improved valve device adapted for downward movement, through a casing or similar string located in a well bore, into engagement with a cooperable seat to close the passage through the casing string.

Another object of the invention is to provide a valve device adapted for downward movement through a well casing into engagement with a cooperable valve seat, in which the device is maintained substantially centered in the well casing to insure its proper coaction with the seat.

Still another object of the invention is to provide a combination cementing plug and valve member which can maintain fluent cementitious materials and other fluid materials in a well casing separate from each other, and which can also engage a valve seat, as one provided in a sleeve valve member, to close the passage through the seat and effect hydraulic shifting of the sleeve valve member in the casing string. In a more limited sense, an object of the invention is to provide a combination top cementing plug and valve member.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section through a well casing having one or more ports, with the ports closed against flow of fluid between the interior and exterior of the casing string;

Fig. 2 is a view similar to Fig. 1, disclosing certain plugs coacting with the sleeve valve portions of the apparatus, with the ports reclosed after having been opened.

As shown in the drawings, a casing collar A is

2

provided at an intermediate point in a string of casing positioned in a well bore. The upper end of the collar may be threadedly attached to an adjacent upper casing section B, while its lower end may be similarly secured to the upper pin 10 of a lower casing section C. The collar is so positioned in the casing string as to insure its location in the well bore at the point where it is desired to eject cement slurry, or other cementitious material, from the casing string into the surrounding well annulus.

The main portion of the collar A consists of a tubular member 11, which, as disclosed in the drawings, is made of two parts 12, 13 to facilitate assembly of the apparatus. The upper threaded bore portion 12, which is secured to the upper casing section B, is suitably attached, as by means of coengaging threads 14 to the lower portion 13 of the tubular member. For the purpose of discharging fluids from the interior of the casing string and collar to the exterior thereof, the tubular member is provided with one or more lateral ports 15. These ports, however, are closed against passage of fluids when the casing string is run in the well bore. They can be opened to permit cement slurry and other fluids to be discharged therethrough; and they can be again closed to prevent further passage of fluids between the interior and exterior of the collar.

In order to accomplish the above-noted purposes, a lower sleeve valve member 16 is disposed in the tubular member 11. This sleeve valve member is provided with spaced ring grooves 17, 18 carrying suitable side seals 19, 20 such as rubber "O" rings, for preventing leakage of fluids in both longitudinal directions around the exterior of the sleeve and out through the ports 15. The lower seal ring 20 is engageable with an in-turned flange 21 on the tubular member 11, whereas the upper seal ring 19 is engageable with the inner surface of an upper sleeve valve member 22, which is initially maintained above the ports 15, but which can be shifted downwardly to close these ports. This upper member is made of two parts, including a lower tubular sleeve 23, preferably made of a difficultly drillable material, such as steel and a readily drillable upper portion 24, of magnesium, aluminum, and the like, piloted within the steel member, and having a shoulder 25 engaging the upper end of the latter. Leakage between these two portions is prevented by a suitable side seal 26, such as an O ring, located in an external groove 27 in the drillable portion and engaging the inner wall of the steel portion 23.

As indicated above, the upper sleeve valve member 22 is disposed initially in an upper position clear of the ports 15 (see Fig. 1). The two portions 23, 24 of this valve are held together and in their upper location by one or more frangible devices, in the form of shear screws 28, extending through them and through the tubular member 11. Disruption of the screws 28 enables the upper sleeve valve member 22 to be shifted downwardly to a position closing the ports 15.

The lower sleeve valve member 16 is nested or piloted within the upper sleeve valve member 22, with its side seals 19, 20 disposed on opposite sides of the ports 15. The lower member 16 is held in such position initially by one or more shear screws 29 extending through the tubular member 11 and threaded into the lower sleeve member. These shear screws dispose the lower seal ring 23 in contact with the inturned flange 21, preferably a short distance above the lower end of the latter. Below the flange 21, the lower sleeve valve has an enlarged diameter portion 30 for slidable engagement with the enlarged bore 31 of the tubular member.

The upper portion 32 of the lower sleeve valve is reduced in external diameter to provide an annular space 33 in conjunction with the upper sleeve valve 22 through which cement slurry, and other fluent substances, may flow when the lower sleeve valve has been shifted downwardly to port opening position. The lower sleeve valve 16 preferably abuts the drillable portion 24 of the upper sleeve valve, in order to hold the overall dimensions of the combined sleeve valve structure to a minimum.

The central bore 34 through the upper drillable portion 24 of the upper sleeve valve is preferably tapered inwardly in a downward direction, merging smoothly into a corresponding bore 35 in the lower sleeve valve 16. In fact, the lower bore 35 forms a continuation of the upper bore 34.

The collar A is made up in the casing string with the parts occupying their initial position as disclosed in Fig. 1. The upper sleeve valve 22 is disposed above the ports 15, and the lower sleeve valve 16 is located in its upper position, with its seals 19, 20 on opposite sides of the ports. As a result, any fluids pumped down through the casing string will pass through the convergent bores 34, 35 in the upper and lower sleeve valve members to some lower point in the casing string, such as a casing shoe (not shown), from which the fluids are ejected into the well bore surrounding the casing. If the collar is employed in connection with a multiple stage cementing operation, a charge of cement slurry may be pumped down the casing string for ejection from the casing shoe. A flexible top cementing plug (not shown) of the character disclosed in my Patent No. 2,370,833 may be used at the upper end of the cement slurry, and this plug will be capable of passing through the convergent bores 34, 35 of the upper and lower sleeve members 24, 26 without shearing the screws 28, 29, the convergent wall of the bores 34, 35 facilitating inward compression of the flexible or rubber plug.

Following the discharge of the lower quantity of cement slurry from the casing, it is desired to open the ports 15 in the collar and discharge a second quantity of cement slurry through these ports for upward passage around the casing string. A tripping device, in the form of a plug or valve member 36, is pumped down the casing string, or is allowed to gravitate through the

fluid in the casing string into engagement with the tapered wall 35 of the lower sleeve (see Fig. 2). This plug is of such dimensions as to pass through the upper sleeve 24, but is of greater diameter than the minimum diameter through the lower sleeve 16, to insure its seating in the latter and its closing of the tapered bore 35.

The lower plug member 36 gravitates rapidly through the fluid in the well bore until the head 10 seal 39 engages the tapered wall 35 in the lower sleeve 16 in leakproof relation. The fluid in the casing above the collar and plug 36 may then be subjected to pressure of an amount sufficient to overcome the shear value of the lower screws 29, disrupting them and shifting the lower sleeve 16 downwardly to a position in which its upper seal ring 19 is disposed below the ports 15 (see Fig. 2). Downward movement of the lower sleeve is limited by its engagement with a suitable stop, which, in the present instance, is provided by the upper end 10a of the lower casing section C.

Cement slurry, or other fluids, may now be pumped down the casing string, passing over the upper end of the lower sleeve 16 and through the annular space 33 between it and the upper sleeve 22, for discharge through the collar ports 15. After the desired quantity of cement slurry has been thus ejected through the collar, it is desired to close the ports by shifting the upper sleeve 22 downwardly. This latter purpose may be achieved by placing a top cementing plug 47 at the upper end of the charge of cement slurry, and causing it to engage the tapered wall 34 of the upper drillable portion 24 of the upper sleeve valve member 22, closing the bore through the drillable portion and allowing the fluid in the casing thereabove to be pressurized to an extent sufficient to shear the upper screws 28 and shift the upper sleeve 22 downwardly over the ports 15, as explained in my parent application above referred to.

An upper seal 48 on the steel sleeve portion 23 will be disposed above the ports 15 to prevent passage of fluids between the ports along the upper portion of the sleeve 22, while downward passage of fluids along the sleeve 22 is prevented by a lead seal ring 49 carried by the sleeve and adapted to be forced against a shoulder 50 formed in the tubular member 11 between its flange 21 and the ports 15.

The lead seal ring 49 is slidable along the wall of the tubular member 11, its inner surface being tapered in a downward and inward direction and engaged by a companion taper 51 on the upper sleeve valve member 22. The lead seal is prevented from removal from the sleeve valve member by an internal flange 52 on the ring fitting within a companion groove in the sleeve 22.

When the upper sleeve valve member is shifted downwardly, the lower end of the lead seal ring 49 engages the shoulder 50, which enables the tapered portion of the sleeve to wedge the ring firmly against the wall of the tubular member 11 and the shoulder 50, preventing leakage of fluids between the lower end of the sleeve 22 and the tubular member. As indicated above, the O ring 48 will engage the tubular member 11 above the ports 15, in order to prevent leakage of fluid along the upper portion of the upper sleeve 22.

The upper sleeve valve 22 is held in its closed position across the ports 15 by a suitable latch device which may take the form of a split, inherently expandible, ring 53 disposed in an ex-

ternal groove 54 in the sleeve 23 and having teeth or wickers 55 adapted to engage companion internal teeth or wickers 56 formed in the side wall of the tubular member 11. This latch arrangement prevents the sleeve 22 from moving upwardly after it has been shifted to port closing position.

The top cementing plug and valve 47 includes a spherical plug device 56 suitably secured to a standard top cementing plug 57, which may have the usual wooden body 58 and cup leathers 59 adapted to slidably seal with the wall of the casing string. The lower plug device may consist of a generally spherical body 60 of readily drillable material, such as magnesium, aluminum, synthetic resin and the like, which has a screw 61 cast within it. This screw is threaded into the wooden body 58 and serves to attach the standard plug to the lower spherical valve body 60. In order to insure against leakage between the lower plug 47 and the upper sleeve valve member 22, a spherical seal member 62 of rubber, or similar material, may be mounted on the body 60, the upper end of the seal having an inwardly directed flange 63 received within a companion groove in the body. A wiper device 59a may also be clamped between the body 58 and the spherical body 60.

The combination top cementing plug and valve member 47 serves effectively to separate the cement slurry from the displacement fluid in the casing on top of the plug. The top sealing members 59 on the cementing plug portion of the device slidably seal against the wall of the well casing B during downward movement of the device therewithin. In addition, the wiper ring 59a also engages the casing wall. By their engagement with the casing, the sealing cups 59 and the wiper ring 59a keep the valve body 58 centered in the casing and insure its proper location within the upper sleeve valve portion 22, with its spherical seal 62 firmly engaging with the tapered seat 34 in the sleeve valve.

Thus, the combined cementing plug and valve device not only serves to insure the ejection of substantially all of the cement slurry through the casing ports 15, but also insures the timely closing of the upper sleeve valve 22 over the ports, as a result of engagement of the lower valve member 56 in the upper portion 24 of the sleeve valve 22. This action takes place hydraulically as an incident of pumping the device down the casing string, for the purpose of ejecting the cement slurry through the collar ports 15.

The portions of the cementing plug and of the valve member 47 are preferably made of readily drillable materials, so as to insure their disintegration by drill bit after the ejected cement has

set and hardened. In this manner, the casing bore may be left free from obstructions or restrictions.

The invention claims:

1. In apparatus of the character described: an imperforate well cementing plug having a packing adapted to slidably seal with the wall of a well casing; and a valve head rigidly secured to and depending substantially below the lower end 10 of the plug and having a generally hemispherical downwardly facing surface adapted to seal against a companion seat in the casing.

2. In apparatus of the character described: an imperforate well cementing plug having a packing adapted to slidably seal with the wall of a well casing; a head rigidly secured to and depending substantially below the lower end of said plug and having a generally hemispherical downwardly facing surface; and a generally hemispherical elastic seal on the downwardly facing of said head.

3. In apparatus of the character described: an imperforate well cementing plug having longitudinally spaced upper and lower packing elements 25 adapted to slidably seal with the wall of a well casing; a valve head secured to and depending from the lower end of said plug and securing said lower packing element to said plug; said head having a generally hemispherically curved downwardly facing surface; and a downwardly facing elastic hemispherical seal on the hemispherical surface of said head.

4. In apparatus of the character described: an imperforate well cementing plug having a packing adapted to slidably seal with the wall of a well casing; a valve head at the lower end of said plug having a downwardly facing generally hemispherical surface; a generally hemispherical elastic seal on said surface of said head; and means secured to said head and extending upwardly into said plug for rigidly securing said head to said plug.
